ABSTRACT OF THE DISCLOSURE

A method of manufacturing an electrical connector in which a sleeve of dielectric material is secured within a metal tube, comprising the steps of inserting a dielectric sleeve of thermo-plastics material into an open ended metal tube having an internal recess, inserting a core member into the dielectric sleeve, axially compressing the dielectric sleeve under heat to mold the dielectric sleeve between the inside surface of the metal tube and the core member, and force dielectric sleeve material into the recess, allowing the dielectric sleeve to set, and removing the core member from within the dielectric sleeve.

This invention relates to a method of manufacturing an electrical connector, particularly a coaxial electrical connector, and to a connector manufactured by the method.

Known coaxial electrical connectors include an inner contact member, normally in the form of a pin, which is surrounded by a dielectric member of electrically insulating material, the dielectric member serving to locate the inner contact member within an outer contact member which surrounds the dielectric member. The dielectric member is usually secured within the outer contact member, and it is known so to secure the dielectric member by crimping the outer contact member onto the dielectric member.

Difficulty is presented, particularly with coaxial connectors of small sizes in holding all of the connector parts in appropriate relative positions during assembly of the connector to a coaxial conductor. Coaxial connectors tend to be bulky in relation to the conductor and also expensive to manufacture and it is an object of the invention to simplify the manufacture of an assembly of a dielectric member within a metal tube for use in a coaxial connector and so to facilitate and economise in the cost of manufacture and allow easier assembly of the connector to a coaxial conductor.

According to the present invention, a method of manufacturing an electrical connector, in which a sleeve of dielectric material is secured within a metal tube, is characterised by the steps of inserting a dielectric sleeve of thermo-plastics material into an open-ended metal tube having an internal recess, inserting a core member into the dielectric sleeve axially compressing the dielectric sleeve under heat to mould the dielectric sleeve between the inside surface of the metal tube and the core member, and force dielectric sleeve material into the recess, allowing the dielectric sleeve to set, and removing the core member from the assembly.

The present invention will now be described, by way of example, with reference to the accompanying drawings, in which:

FIG. 1 is an axial sectional view of an outer contact member for a coaxial electrical connector;

FIG. 2 is a section on the line II—II of FIG. 1;

FIG. 3 is a section on the line III—III of FIG. 2, but with a dielectric sleeve and a core member in position within the outer contact member; and

FIG. 4 is a section on the line IV—IV of FIG. 2, but with a dielectric sleeve and an inner contact member in

2

position within the outer contact member, and a spring member in position around the outer contact member.

The outer contact member shown in FIGS. 1 and 2 is in the form of a circular cross-section metal tube 1 of substantially uniform wall thickness, having two integrally formed parts 2 and 3 of mutually different diameter. The larger diameter part 2 of the tube 1 has a portion of its wall cut away to provide a window 4. The small diameter part 3 of the tube 1 has a circumferential rib 5 formed in it to provide an annular recess 6 within the part 3.

For use of the outer contact member in a coaxial connector, as shown in FIG. 4, the dielectric sleeve 7 of FIGS. 3 and 4 is secured within the tube 1. The circular cross-section sleeve 7 of dielectric material, the outer diameter of which is substantially equal to the inside diameter of the part 3 of the tube 1, is slidably inserted into the part 3. A circular cross-sectional metal core member 8, FIG. 3, is then slidably inserted into the dielectric sleeve 7, the core 8 having three portions 9, 10 and 11 of mutually different diameter. The diameter of the largest diameter portion 11 of the core 8 is substantially equal to the inside diameter of the part 3 of the tube 1, and this portion 11 provides a shoulder 12 at its junction with the portion 10 of the core 8, which engages an end face 13 of the dielectric sleeve 7. The intermediate core portion 10 of intermediate diameter and the end core portion 8 of smallest diameter extend within the sleeve 7 and the end portion 8 projects from the sleeve end.

A circular cross-section pressure member (FIG. 3) is then inserted into the part 2 of the metal sleeve 1, the pressure member having a main body 13 of a diameter substantially equal to the inside diameter of the part 2 of the tube 1 and a boss 14 at one end of the body 13, the boss 14 having a diameter substantially equal to the inside diameter of the part 3 of the tube 1. The junction between the parts 13 and 14 of the pressure member forms a shoulder 15 which engages the inner end face 16 of the part 3 of the tube 1, the free end of the boss 14 forming a stop which serves to position the dielectric sleeve 7 within the tube 1. An axial blind bore 17 extends into the pressure member 13, 14 from the free end of the boss 14, the bore 17 having a diameter slightly greater than the diameter of the portion 9 of the core 8 which is slidably received within the bore 17.

The tube 1 containing the dielectric sleeve 7, the core 8 and the pressure member 13, 14 is then positioned within a heating jacket, not shown, and the core 8 and the pressure member 13, 14 urged axially towards each other by means not shown. The heat from the heating jacket softens the material of the dielectric sleeve 7, and as the core 8 moves toward the pressure member 13, 14 the portion 9 of the core 8 entering the bore 17 in the pressure member 13, 14, the dielectric sleeve 7 is compressed axially and moulded between the inside surface of the part 3 of the tube 1 and the core 8. Material of the dielectric sleeve 7 is forced into the annular recess 6 in the part 3 of the tube 1, and the shoulder 15 of the pressure member engages the face 16 of the part 3 of the tube 1 precisely to locate the dielectric sleeve axially within the tube 1.

The assembly is then removed from the heating jacket, and the core 8 and pressure member 13, 14 removed from within the tube 1.

The dielectric sleeve 7 remains secured within the tube 1 against axial movement as a result of the material of the dielectric sleeve 7 positioned within the recess 6 and the tight engagement of the sleeve 7 within the tube portion 3. The inner surface of the dielectric sleeve 7 is profiled by the core member to receive an inner contact member 18, FIG. 4, inserted at the free end of the part 3 of the tube 1. The contact member 18 is suitably of

tubular form having a leading plug portion extending from a rear wire connecting portion of enlarged diameter. The leading plug portion extends through the reduced diameter leading end of the sleeve 7, which was formed by the core portion 8, and projects from the sleeve 7 within the forward tube portion 2. The rear wire connecting portion of member 18 is disposed within the larger diameter rear end of the sleeve 7 defined by core portion 10 with the transition between the different portions of the contact member 18 engaging a complementary shoulder defined between the different diameter bores of the sleeve 7. In assembling the connector to a coaxial conductor, not shown, the wire connecting portion of contact member 18 is secured to a core conductor by crimping and then inserted into the sleeve 7 to the position of FIG. 4. The rear end of the tube portion 3, the right hand end in FIG. 4, is inserted between the dielectric and the outer conductor of the coaxial conductor and suitably secured in known manner by a surrounding crimping ferrule not shown.

A spring member 19 (FIG. 4), is secured around the part 3 of the tube 1 adjacent the inner end of the part 2 of the tube 1. The member 19 has three outwardly directed arms 20 which, in use, serve to secure the connector in a housing. The arms 20 are angularly spaced by 90°, and the centre one has a further arm 21 extending in line therewith over the window 4 in the part 2 of the tube 1. The arm 21 is bent at its free end to form an inwardly extending rib 22 which in use engages a male terminal inserted into the part 2 of the tube 1, to secure the male terminal to the tube 1.

Although the invention has been described above in relation to a female coaxial electrical connector, it is equally applicable to a male coaxial electrical connector.

I claim:

1. A method of manufacturing an electrical connector in which a sleeve of dielectric material is secured within

5 a metal tube, comprising the steps of inserting a dielectric sleeve of thermo-plastics material into an open ended metal tube having an internal recess, inserting a core member into the dielectric sleeve, axially compressing the dielectric sleeve under heat to mould the dielectric sleeve between the inside surface of the metal tube and the core member, and force dielectric sleeve material into the recess, allowing the dielectric sleeve to set, and removing the core member from within the dielectric sleeve.

10 2. A method according to claim 1, in which the dielectric sleeve is compressed between a shoulder on the core member intermediate its ends, and a pressure member inserted into the metal tube from the opposite end to and about the core member.

15 3. A method according to claim 2, in which the dielectric sleeve is precisely located within the metal tube while being compressed, by a shoulder on the pressure member engaging an internal shoulder of the metal tube.
